UNITED STATES PATENT OFFICE.

ARTHUR W. HAWKINS, OF CHICAGO, ILLINOIS, ASSIGNOR TO CHICAGO RAILWAY EQUIPMENT COMPANY, OF CHICAGO, ILLINOIS, A CORPORATION OF ILLINOIS.

CAR-LADDER.

1,311,348.

Specification of Letters Patent. Patented July 29, 1919.

Application filed July 14, 1917. Serial No. 180,600.

To all whom it may concern:

Be it known that I, ARTHUR W. HAWKINS, a citizen of the United States, residing at the city of Chicago, county of Cook, State of Illinois, have invented a certain new and useful Improvement in Car-Ladders, of which the following is a full, clear, and exact description, such as will enable others skilled in the art to which it appertains to make and use the same, reference being had to the accompanying drawings, forming part of this specification.

This invention relates to a ladder construction, and pertains particularly to a form of ladder designed for use on railway cars.

The several objects of my invention include the provision of a ladder which may be fabricated and assembled very economically, due both to the interchangeability of its various parts and the nature of its construction; and the provision of a ladder in which the rungs are held securely in the stiles in such fashion as to prevent their turning or working out, the construction at the same time being such as to permit the removal individually of any rung which may become bent or broken in use, or of the stiles individually.

Other objects of my invention will be obvious or pointed out hereinafter, reference being had to the accompanying drawings in which

Figure 1 represents a partial end elevation of a box car showing a ladder in front elevation and another ladder in side elevation;

Fig. 2 is a detail illustrating in side elevation the form of the stile members and the manner of attachment thereof to the car;

Fig. 3 is a detail showing the same parts in front elevation;

Fig. 4 is a detail illustrating a transverse section through the stile members;

Fig. 5 is a front elevation of a modified form;

Fig. 6 is a section of the same taken on line 6—6 of Fig. 5;

Fig. 7 is a perspective illustrating a detail of another modified form;

Fig. 8 is a perspective illustrating a detail of a third modified form.

Referring to the illustrations by means of the reference numerals applied, let it be un-

derstood that the numeral 1 designates the stile members of the ladder which may be in the form of angle bars having portions offset as at 1^a to provide attaching brackets. These stile members are arranged to be attached to the supporting wall by means of suitable fastenings 2 seated in said brackets, and by means of fastenings 5 passing through spacers 4 disposed intermediate the brackets. This means of forming a mounting supports the stile members spaced apart from the supporting wall, one flange of the angle bar of which they are comprised extending substantially parallel with the wall, and the other extending substantially perpendicularly thereto. At proper intervals in the outstanding or perpendicular flange are punched slots or apertures for the reception of the rungs 6. The latter are in the form of bars or rods formed with a head 6^a at one end and with a transverse aperture adjacent the other extremity 6^b. If desired, portions of the material adjacent the extremities of the rungs may be flattened or spread into angular form, as in the fashion illustrated in Fig. 4. In the event of the rungs being thus formed, the apertures in the stiles will, of course, be of suitable angular form to receive the flattened portions.

The rungs are inserted in the apertures in the stiles, the heads of the rungs coming up against the outstanding flange of one of the stiles, and the apertured extremities of the rungs projecting through the slots in the other stile. As it is contemplated that the slots in the stiles shall be in alinement longitudinally thereof, it will be seen that the apertures 6^b in the extremities of the rungs will be disposed in alinement, in which position they will receive the retaining rods 7. Each of these retaining rods is designed to be inserted through the apertures 6^b of a plurality of rung members, said retaining rods being held against removal therefrom by any suitable device 8. The retaining rods, being comparatively slender, necessarily will have the requisite amount of flexibility to permit their being accommodated to any slight irregularities in the alinement of the apertures 6^b.

With the parts thus assembled, it will be observed that each of the rungs is maintained against rotation by the associated retaining rod, which latter is itself held in

proper alinement by virtue of its connection with a plurality of the rungs. In the event the rungs are of flattened form, they are further retained against rotation by virtue of their engagement with the stiles. While the rungs are thus securely retained in position and held against rotation, any of them are quickly and readily removable without requiring the detachment of the 10 stiles, as the removal of the fastening 8 and retaining rod 7 leaves the rungs free to be removed individually. When the retaining rod 7 is in place, it lies snug against the outstanding flange of the associated stile, in which position it is protected from injury.

To facilitate assembly and removal of the stiles, I supply suitable brackets 9 in the form of castings or forgings arranged to 20 be bolted or otherwise suitably secured to the supporting structure. These brackets may be disposed in rows, the rows being spaced apart the proper distance to accommodate the width of the latter, and the individual brackets in respective rows being disposed opposite one another. These brackets have outwardly extending portions 9^a disposed counterfacing and formed with apertures such as are adapted to receive the 25 extremities of rung members 6. Some of the brackets on each side are apertured to permit passage of the rungs therethrough, and others of the brackets on each side are permitted to receive only the flattened or de- 30 formed extremities of the rungs. The stiles are similarly apertured at the points where they are to be associated with the respective forms of brackets. Accordingly, when the 35 stiles are disposed in association with the brackets, rungs may be passed through both the oppositely disposed brackets and the stiles, the head of a rung coming up against the extension 9^a of a bracket on one side and the other extremity of the rung being se- 40 cured by a removable fastening member such as the rod 7 or the bolt or cotter pin 7'. In Figs. 5, 6, and 7, I show the stiles thus mounted in the form of flat strips, while in Fig. 8 I show a stile in the form of an angle 45 member, a part being deflected at 1^b to facilitate the alinement of a laterally deflected portion 1^c with the extremities of the rung members 6. It is obvious, however, that the stiles may be in any of a variety of forms 50 other than a flat strip or a simple angle. In the forms illustrated in Figs. 7 and 8, the uppermost and lowermost brackets 9 are apertured to accommodate the laterally deflected portions of the stile members, thus 55 providing a mounting for them, in which mounting they are secured by a retaining member 7 or 7'. With respect to the forms illustrated in Figs. 5 to 8 inclusive, it is to be observed 60 that in addition to providing for the indi-

vidual assembly of the rung members, they also facilitate the individual removability of the stile members, and thus contribute further to economy in the assembling and repairing of the device.

While I have called attention above to the desirability of the retaining members 7 having engagement with a plurality of rung members for preventing the rotation of the latter when they are not formed with angular portions for engaging the stiles, it is obvious that, when the rung members are formed with the angular stile-engaging portions, they will be effectively held against rotation, and they may be retained against 80 longitudinal displacement by individual retaining members 7.

The ladder structure thus formed is very economical to manufacture and to install, the several parts are interchangeable, and injured portions may be removed and replaced without requiring the removal of the ladder from the supporting wall.

I am aware that my invention may be embodied in forms other than the specific embodiment illustrated and described, and it is my intention that the appended claims comprehend all such modifications.

What I claim is:

1. A ladder structure including a bracket member, a stile member and a rung member removably associated with said bracket and stile members to retain them in assembled relationship, and means for holding said rung member in position, said means being removable so as to permit the rung member to be removed to enable the dismantling of the stiles.
2. In a ladder structure, spaced supporting brackets provided with apertures, stile members arranged adjacent to said supports and provided with apertures which coincide with the apertures in the brackets, and a rung member seated in the apertures of said brackets and stile members for holding the same in assembled relation.
3. In a ladder structure, spaced supporting brackets provided with apertures, stile members arranged adjacent to said supports and provided with apertures adapted to coincide with the apertures in the brackets, certain of which apertures are angular, and a rung member seated in the apertures in said brackets, and stile members for holding the same in assembled relation, portions of said rung members fitting the angular apertures so as to prevent the rotation of said rung members.
4. In a ladder structure, spaced supporting brackets provided with apertures, stile members arranged adjacent to said supports and provided with apertures adapted to coincide with the apertures in the brackets, rung members seated in the apertures in said brackets, and stile members for holding

the same in assembled relation, and rung members positioned upon said stile members between the rungs that are seated in the brackets.

5 5. In a ladder structure, spaced supporting brackets provided with apertures adapted to coincide with the apertures in the brackets, a rung member seated in the apertures in said brackets, and stile members for holding the same in assembled re-

lation, and means for preventing the withdrawal of the rung members from said brackets and stile members.

In testimony whereof I hereunto affix my signature, this 6th day of July, 1917.

ARTHUR W. HAWKINS.
